CLAIM

The ornamental design for a watering nozzle, as shown and described.

DESCRIPTION

FIG. 1 is a first top perspective view of a watering nozzle, according to my new design;

FIG. 2 is a second top perspective view of the watering nozzle;

FIG. 3 is a first bottom perspective view of the watering nozzle;

FIG. 4 is a second bottom perspective view of the watering nozzle;

FIG. 5 is a front side elevational view of the watering nozzle;

FIG. 6 is a rear side elevational view of the watering nozzle;

FIG. 7 is a top view of the watering nozzle;

FIG. 8 is a bottom view of the watering nozzle;

FIG. 9 is a right side elevational view of the watering nozzle;

FIG. 10 is a left side elevational view of the watering nozzle;

FIG. 11 is a left side elevational view of the watering nozzle in a first alternate position;

FIG. 12 is a left side elevational view of the watering nozzle in a second alternate position;

FIG. 13 is a left side elevational view of the watering nozzle in a third alternate position; and,

FIG. 14 is a left side elevational view of the watering nozzle in a fourth alternate position.

The broken lines in the figures are included for the purpose of illustrating unclaimed portions of the watering nozzle and form no part of the claimed design.

1 Claim, 14 Drawing Sheets
